UNITED STATES PATENT OFFICE.

EDWARD SMITH, OF CHICAGO, ILLINOIS.

DESIGN FOR A PICTURE-FRAME.

54,784.

Specification for Design.

Patented Mar. 23, 1920.

Application filed May 3, 1919. Serial No. 294,589. Term of patent 3½ years.

To all whom it may concern:

Be it known that I, EDWARD SMITH, a citizen of the United States, residing at Chicago, in the county of Cook and State of Illinois, have invented a new, original, and ornamental Design for Picture-Frames, of which the following is a specification, reference being had to the accompanying drawing, forming part thereof.

The figure is a plan view of a picture frame showing my new design.

I claim:

The ornamental design for a picture frame as shown.

In testimony whereof I affix my signature in the presence of a witness.

EDWD. SMITH.

Witness:

DANIEL A. BRENNAN.
